(57) **CLAIM**

The ornamental design for an adjustable garment, as shown and described.

DESCRIPTION

FIG. 1 is a perspective view of an adjustable garment, showing our new design;

FIG. 2 is a front plan elevation view of FIG. 1 thereof; FIG. 3 is a first side elevation view of FIG. 1 thereof, with a second side elevation view being a mirror image thereof; FIG. 4 is a top plan view of FIG. 1 thereof, with the bottom plan view being a mirror image thereof;

FIG. 5 is a front plan elevation view of FIG. 1 thereof; FIG. 6 is another perspective view of FIG. 1 thereof, showing the garment in use;

FIG. 7 is a front plan view of FIG. 6 thereof; and, FIG. 8 is a first side elevation view of FIG. 6 thereof, with a second side elevation view being a mirror image thereof. The broken away symbols in FIG. 5 indicate the appearance of any portion of the article between the break lines forms no part of the claimed design.

The dash-dash broken lines shown in the drawings show unclaimed environment and form no part of the claimed design.
